CARRYING BAG OR SIMILAR ARTICLE

Anthony N. D'Elia, Riverdale, and Edward M. Stolarz,
Yorktown Heights, N.Y., assignors to Reliable Luggage,
Incorporated, West Pittsburg, Pa., a corporation of Pennsylvania

Filed Dec. 1, 1967, Ser. No. 9,610

Term of patent 14 years

Int. Cl. D3—02

U.S. Cl. D87—5

FIG. 1 is a front elevational view of a carrying bag or similar article embodying our new design;

FIG. 2 is a rear elevational view thereof;

FIG. 3 is a side elevational view thereof;

FIG. 4 is a side elevational view of the opposite side from that shown in FIG. 3;

FIG. 5 is a top plan view thereof; and,

FIG. 6 is a bottom plan view thereof.

We claim:

The ornamental design for a carrying bag or similar article, as shown and described.
